FLOAT

Antonio Perri, McKees Rocks, Pa.

Application August 15, 1934, Serial No. 739,947

4 Claims. (Cl. 9—2)

My invention relates broadly to floats, and more particularly to floats for bathers at pleasure resorts. An important characteristic of my invention is its knockdown or collapsible nature 5 whereby it may be readily stored or transported in passenger vehicles or other conveyances.

My invention may be used not only for amusement purposes but it also has marked utilitarian advantages. By its use bathers who cannot ordinarily safely go into deep water may safely do so with my apparatus. This permits them to avoid the necessity of bathing, for instance, on muddy shores. It can also be used to advantage by swimmers who desire to swim in midstream with 10 a safe resting place at hand and since it is provided with propelling means, it can also advantageously be used by its occupant for following swimmers. It is capable of keeping afloat a number of persons who may take hold of its 15 sides for support. It is also particularly useful to campers who may dress only in their bathing suits and who wish to go some distance on the water for supplies, since it readily affords support above the water for such supplies.

20 Since it may be provided with an awning, it is capable of protecting the user against the heat of the sun at all times while permitting him to be for the most part submerged. It may also advantageously be used as a floating bath 25 enabling one to wash in the selected water away from muddy banks.

By providing children with safety belts attached to its sides it is possible for them to play in the water regardless of its depth with perfect 30 safety.

Other novel features and advantages of my invention will hereinafter appear.

In the accompanying drawings, showing for purposes of exemplification but without limiting 35 my invention or claims thereto, certain particular 40 embodiments of my invention.

Fig. 1 is a top plan view of one embodiment of 45 my invention;

Fig. 2 is a vertical section on the line II—II

45 of Fig. 1;

Fig. 3 is a detail vertical section through one of the sides taken on the line III—III of Fig. 1;

Fig. 4 is a detail vertical section of the swiveled 50 oar lock on the line IV—IV of Fig. 1;

Fig. 5 is a perspective view of my awning showing the manner of its attachment to the sides, and

Fig. 6 is a view showing my apparatus collapsed for storage or transportation.

55 Referring to the drawings, my device is shown

as comprising a rectangular bottom frame 1 with its sides and ends permanently connected at the corners by suitable means. Each side comprises a top horizontal member 2 permanently attached to vertical members 3 and 4 at its opposite ends respectively, and the lower ends of the vertical members are hinged as shown at 5, to the corresponding side frame member of the bottom 1, whereby each side may be folded downwardly upon the bottom when the float is collapsed. If 10 desired, the lower ends of the vertical members 3 and 4 may be permanently connected by a frame member. The opposite sides 2 may be conveniently held fixed in their raised positions by members or bars 6 and 7 interposed between 15 their opposite ends, as shown in Fig. 1, the bar 6 being conveniently hinged at 8 to one end of the top side bar 2 and being fastened at its opposite end to the opposite side bar 2 by means of a wing nut and bolt 9 passing through an angle 20 iron 10 attached to said side. The end piece 7 is similarly attached at the forward ends of the top side bars 2 but is preferably hinged to the side opposite to that to which the bar 6 is hinged to facilitate folding. These members are adapted 25 to swing inwardly against their respective sides when the device is collapsed.

Float members 11 are provided on the outer surface of the sides 2 to keep the device at the desired depth in the water. These members 30 may conveniently be collapsible to facilitate compactness when the device is folded. As shown in Fig. 3, the float member comprises an outer casing of fabric, conveniently formed of a main tubular portion 12, a loop 13 containing a reinforcing strip 14 of wood or metal or other suitable material, the loop being closed by a seam 15, the loop assemblage being connected to the upper bar 2 by a bolt 16 passing through them. The tubular portion is preferably attached at its bottom, also, to the corresponding side frame member of the bottom as shown at 17. The casing is provided with an inner tube 18 which may be inflated and deflated through the valve 19.

The seat 20, conveniently made of a frame 21 and slats 22, rests at its opposite side on the opposite side frame members, respectively, of the bottom and this seat may conveniently be stationed centrally to balance the float as shown in the new sketch Fig. 3. The seat may be conveniently attached by means of four Z plates 23, with one side resting upon a bottom side member and attached thereto by bolts 24. The other end of the Z members passing under the seat frame 21, and being secured by the bolts 25, it 55

is obvious that the seat is centered stationary to the bottom frame.

The apparatus may be propelled by means of oars 26, conveniently swiveled at the top of the sides, as shown in Fig. 4, by means of a U-shaped metal support 27, to which the oar is pivotably attached by a bolt 28, the support 27 being swiveled to the side by a bolt 29 passing through the top side frame member, the frame member being preferably protected by a metal angle plate 30 and a washer or ball-bearing 31, or the like, being employed to separate the members 27 and 30. When the float is to be folded, the oars may be turned in alignment with the sides, or may be entirely removed.

I further provide a collapsible foot rest 32 extending through the forward end of the bottom, which may conveniently be made of a flexible fabric sheet 33, such as canvas, or the like, the upper end of which may be secured as shown in Fig. 2, by passing the same about the forward slat of the seat and securing it between the slat and the side front frame member in any suitable manner. The forward end of the fabric sheet is provided with a foot-board 34 permanently attached thereto, and the foot-board is held substantially at right angles to the sheet by means of a rope 35 knotted at one end passing downwardly through a hole in the foot-board upwardly through a second hole therein, and thence through an eyelet 36 at the bottom of a side end member, thence upwardly through the eyelet 37 at the top of the side end member, thence across the float and downwardly through similar eyelets at the opposite side, and thence to the corresponding end of the foot-board to which it is secured in a manner similar to its other end. The foot-board may be readily adjusted to different lengths by taking up the rope at its ends, making new knots, or by knotting the portion of the rope crossing from one side to the other, or by turning the foot-board to fold the fabric and rope.

I may conveniently provide a seat back comprising a suitable fabric 40, such as canvas, duck, or the like, attached at its lower end to the rear end slat of the seat in any appropriate manner such as that described for securing the foot rest fabric to the front slat of the seat. Attached to the upper end of the seat back fabric by any suitable means is a cross-bar 41, having eyelets 42 at its ends, which may be conveniently formed in the ends of a steel bar or plate 43 rigidly attached to the bar 41, although it is obvious that any other suitable construction may be employed. The eyelets 42 are located a short distance from the top side members 2 and are connected thereto by means of a spring 44 having one of its ends passing through said eyelet and its other end through the eyelet of a plate 45 permanently secured to said top side member 2 in any appropriate manner. The plate 45 is preferably provided with a plurality of eyelets to permit adjustment of the back member.

When it is desired to fold the apparatus for storage, the springs may be removed from the plates 45 and the seat back folded on the bottom.

I further provide eyelets 46 which may conveniently be formed on the hinged plate 5 into which the free ends of the springs may be inserted causing the back to assume a horizontal position in the plane of the bottom should it be desired to operate without a back, or should two bathers, sitting back to back, desire to occupy the float. The back may be left in this position when it is desired to fold the float.

An awning may be conveniently provided for my float by attaching two upright rods 50, bent at their upper ends into the configuration desired for the awning, and attached at their lower ends by means of bolts 51 passing through holes in the flattened portion 52 of the rods. The awnings 53 may be conveniently attached to these rods to freely slide thereon by means of rings 54 attached to the sides of the awnings and passing about said rods. The upper end of the awning is preferably provided with a rod 55 having projecting ends adapted to engage in the hooked portions 56 of the rods. It is thus seen that the awning may be raised or lowered as the user desires, and when it is desired to knock down the assembly, it is only necessary to remove the bolts 51, which release the awning from the float. The awning may then be compactly packed with the float when collapsed.

While I have shown my apparatus designed for the use of one occupant, it is obvious that it may be extended in tandem to provide for two or more occupants.

It will be understood that many changes may be made in the forms disclosed, within the spirit of my invention, and that many features may be used to advantage without a corresponding use of other features.

I claim:

1. A knockdown bathing apparatus including, in combination, a frame having a bottom; sides hinged to said bottom and foldable thereon; deflatable pneumatic float members attached to the top edges of said sides; oars swiveled to said sides; and members hinged to said sides and foldable thereon; means for detachably connecting the free corners of said sides and end members when raised; a back member detachably connected to said sides; a cover frame comprising side bars detachably secured to said sides, a cover slidably attached to said side bars and provided with means for holding it stretched on said frame, and a flexible leg extension carrying a foot support extending through the forward end of said bottom.

2. A knockdown bathing apparatus including, in combination, a frame having a bottom; sides hinged to said bottom and foldable thereon; deflatable pneumatic float members attached to the top edges of said sides; oars swiveled to said sides; end members hinged to said sides and foldable thereon; means for detachably connecting the free corners of said sides and end members when raised; a back member detachably connected to said sides; and a flexible leg extension carrying a foot support extending through the forward end of said bottom.

3. A knockdown bathing apparatus including, in combination, a frame having a bottom, sides hinged to said bottom and foldable thereon; deflatable pneumatic float members attached to the top edges of said sides; end members hinged to said sides and foldable thereon; means for detachably connecting the free corners of said sides and end members when raised; and a flexible leg extension carrying a foot support extending through the forward end of said bottom.

4. A knockdown bathing apparatus including, in combination, a frame having a bottom; sides hinged to said bottom and foldable thereon; oars swiveled to said sides; means for detachably holding said sides in elevated position, and a flexible leg extension carrying a foot support extending through the forward end of said bottom.
